US00D871983S

(12) **United States Design Patent** (10) Patent No.: **US D871,983 S**
(45) Date of Patent: ** Jan. 7, 2020

(54) **FRONT BUMPER COVER FOR VEHICLES**

(71) Applicants: **HYUNDAI MOTOR COMPANY**, Seoul (KR); **KIA MOTORS CORPORATION**, Seoul (KR)

(72) Inventors: **Tae-Hoon Kim**, Seoul (KR); **Byung-Hak Kang**, Seoul (KR)

(73) Assignees: **Hyundai Motor Company**, Seoul (KR); **Kia Motors Corporation**, Seoul (KR)

(**) Term: **15 Years**

(21) Appl. No.: **35/506,152**

(22) Filed: **Nov. 6, 2018**

(80) **Hague Agreement Data**

Int. Filing Date: **Nov. 6, 2018**

Int. Reg. No.: **DM/103817**

Int. Reg. Date: **Nov. 6, 2018**

Int. Reg. Pub. Date: **Nov. 30, 2018**

(30) **Foreign Application Priority Data**

May 15, 2018 (KR) 30-2018-0022570

(51) LOC (12) Cl. **12-16**

(52) U.S. Cl.

USPC **D12/169**

(58) **Field of Classification Search**

USPC D12/421, 433-434
